FRONT PANEL FOR POWER SUPPLY AND CONTROL UNIT FOR A NANOSECOND SPECTRAL SOURCE

J Perry Smith, Hawthorne, and Ulf R. Helgesson, Sherman Oaks, Calif., assignors to TRW Inc., Redondo Beach, Calif., a corporation of Ohio

Filed Jan. 24, 1966, Ser. No. 733

Term of patent 14 years

(Cl. D26—1)

The single figure is a perspective view of a front panel for power supply and control unit for a nanosecond spectral source showing our new design.

The broken line showing of the housing is depicted for illustrative purposes only.

We claim:

The ornamental design for a front panel for power supply and control unit for a nanosecond spectral source, substantially as shown and described.
